UNITED STATES PATENT OFFICE.

EMIL SCHIERSE, OF CHICAGO, ILLINOIS, ASSIGNOR OF ONE-HALF TO EDWARD C. HAYMAN, OF CHICAGO, ILLINOIS.

TRAVELING HOBBY-HORSE.

1,325,046.

Specification of Letters Patent. Patented Dec. 16, 1919.

Application filed October 21, 1918. Serial No. 258,923.

To all whom it may concern:

Be it known that I, EMIL SCHIERSE, a subject of the Emperor of Germany, and a resident of Chicago, Cook county, and State 5 of Illinois, have invented certain new and useful Improvements in Traveling Hobby-Horses, of which the following is declared to be a full, clear, and exact description.

This invention relates to traveling hobby 10 horses and its primary object is to provide simple and efficient means, of improved construction, for propelling a toy of this kind, when it is rocked. Another object is to provide a traveling, gravity operated, 15 toy vehicle. Another object is to provide a propelling device for hobby horses, which may be readily made inoperative, whereby the toy may be used in others ways for entertainment and pleasure. Other objects and 20 advantages will appear in the following specification and with all of said objects and advantages in view, this invention consists in the several novel features hereinafter fully set forth and claimed.

25 The invention is clearly illustrated in the accompanying drawing, in which:—

Figure 1, is a view partly in side elevation and partly in central, vertical section of a traveling hobby horse, illustrating a simple 30 embodiment of the present invention; Fig. 2, is a view partly in plan and partly in horizontal section, the line of section being indicated at line 2—2 in Fig. 1; Fig. 3, is a side elevation partly broken away 35 of a fragment of the device showing a certain inclined slide, in inoperative position.

Referring to said drawing, the reference character 5, designates the body of the device, which may be constructed to simulate 40 the body of the horse or other animal as desired. The body provides a seat 6, upon which the rider sits while propelling the toy. The legs 7, 7^a, are connected by lengthwise 45 extending bars 8, and secured to said bars are foot boards 9, upon which the rider rests his feet. Rollers or small wheels 10, are rotatively mounted upon cross rods 13, 14, which are secured in the legs 7, 7^a, and large rollers or wheels 11, are ro- 50 tatively mounted on a transverse shaft or rod 12, which is secured in the bars 8, near the middle thereof. The arrangement and proportions of the parts are such that the device may be rocked or oscillated upon 55 the middle rollers or wheels, or the device

may be pushed or pulled along on the middle wheels, and either pair of end rollers.

For propelling the device, an inclined slide 15, is provided, which co-operates with a roller 16, to move the device forward when the rear end of the device is rocked or oscillated in a downward direction. The roller 16, is rotatively mounted on the cross rod 14 and rests upon the inclined track or tread portion 17 of the slide. The lower forward 60 end of said slide rests upon the floor or other surface upon which the device stands, and the upper ends of said slide is supported by a leg 18, which is rigidly secured thereto, and braced by braces 18^a. The 65 slide 15, has two slotted side members 19, secured to it which straddle the rod 14, and act as guards to prevent the roller 16 from running off the track or tread portion of the slide. Preferably, the track portion is made 70 wider at its lower end to permit the roller 16, to run down freely in case the slide occupies a position slightly out of alinement with the body of the device. The rods 13, 14, and rollers 10, 16, are held in place by 75 cotter pins which are inserted in said rods adjacent the rollers 10, 16, and legs 7, 7^a, coiled tension springs 20, secured to the slide and shaft 12, act to draw the slide 80 toward the shaft 12.

In the operation of the device, the child sits on the body 5, and for convenience places his feet on the foot boards 9. The device is rocked upon the shaft 12 of the middle wheels as a fulcrum and when the 85 rear end of the device is rocked in a downward direction, the roller 16 is pressed against the inclined track of the slide, and because of the absence of any considerable amount of friction between the body portion of the device and the surface supporting it, the roller 16, is forced forward down the incline, and therewith the entire device, with the exception of the slide, is moved 90 forward on the middle wheels, until the position shown on dotted lines in Fig. 1, is reached. The forward end of the device is now in an elevated position and when the child rocks the forward end of the device in a downward direction, and the downward pressure is removed from the slide, the coiled springs 20, draw the slide forward, 95 bringing the upper end thereof underneath the roller 16, so that when the device is rocked back, the roller again runs down the 100 105 110

inclined slide and the forward movement again is effected. By rocking the device vigorously, considerable momentum may be attained and the device thereby propelled quite rapidly along the surface supporting it.

When it is desired to use the device without the automatic propelling means, the slide is moved up to the position illustrated in Fig. 3, and attached to a hook 21, by a handle 22, carried by the slide.

It is to be observed that while the body portion has been shown and described as comprising the figure of a horse or other animal, its purpose is to serve as a seat, and that any form of suitable seat may be used in its place. The seat might be omitted as the user could stand on the foot boards and manipulate the device therefrom.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new and desire to secure by Letters Patent:

1. A toy, comprising an oscillatory vehicle, supporting wheels intermediate its ends which continuously support the vehicle at the axis about which it oscillates, and propelling means, actuated by said oscillatory vehicle and coöperating therewith to propel it forward on wheels when said vehicle is oscillated.

2. A toy, comprising an oscillatory, wheeled vehicle, and an inclined slide connected thereto by yielding means and coöperating with said vehicle to move the same forward on the wheels.

3. A toy, comprising a body which forms a seat, wheels supporting said body at a place midway between its ends and said body being capable of oscillation upon said wheels, an inclined slide coöperating with said body to move the same forward relative to the slide, and resilient connecting means between said slide and body.

4. A toy, comprising an oscillatory member having a seat, wheels rockably supporting said member, and an inclined slide having a resilient connection with said member, and coöperating with said member, when rocked in one direction to move the same forward.

5. A toy, comprising a seat portion, wheels upon which said seat portion is rockably mounted, a roller connected to said seat portion, an inclined slide coöperating with said roller to move said seat portion forward when the roller is pressed down upon the slide and yielding connecting means between said slide and seat portion.

6. A toy, comprising a body, having downwardly extending front and rear legs, lengthwise extending bars, connecting the lower ends of said legs, wheels rotatively mounted upon said bars adjacent the middle thereof, a roller rotatively mounted on the rear legs, an inclined slide coöperating with said roller to move the body portion forward when oscillated in a direction to press the roller against the slide, and springs connecting said slide with the body portion. 70 75

7. A toy, comprising a body having downwardly extending front and rear legs, lengthwise extending bars connecting the lower ends of said legs, wheels journaled on said bars adjacent the middle thereof, a roller journaled adjacent the lower ends of the said rear legs, an inclined slide coöperating with said roller to move the body forward when oscillated in a direction to press the roller against the slide, guards at the sides of said slide, and a coiled spring connecting the forward end of said slide with said body. 80 85

8. A toy, comprising a body, having downwardly extending front and rear legs, lengthwise extending bars connecting the lower ends of said legs, a cross shaft extending between said bars near the middle thereof, wheels rotatively mounted on said cross shaft, a cross rod connecting the lower ends of the rear legs, a roller rotatively mounted on said cross rod, an inclined slide coöperating with said roller to move the body forward when the roller is pressed against the slide, slotted guards at the sides of said slide straddling said cross rod, and a spring connecting said slide with said cross shaft, substantially as and for the purpose set forth. 90 95 100 105

9. A toy comprising a body portion, having downwardly extending front and rear legs, centrally located wheels upon which said body portion is rockably mounted, a cross rod secured to the lower ends of the rear legs, a roller rotatively mounted on said cross rod, an inclined slide coöperating with said roller to move the body forward when the roller is pressed against the slide, a coiled spring connecting the slide with the body, and means for holding the slide in inactive position. 110 115

10. A toy, comprising a body, having downwardly extending front and rear legs, rollers journaled at the lower ends of said legs, lengthwise extending bars connecting said legs, wheels rotatively mounted on said bars adjacent their middle, a propelling roller rotatively mounted at the lower ends of the rear legs, and an inclined slide coöperating with said roller to move the body forward when the roller is pressed against the slide, said slide being yieldingly connected to the body. 120 125

EMIL SCHIERSE.
